Specification for Design.

Patented Aug. 30, 1921.

Application filed January 6, 1921. Serial No. 435,520. Term of patent 3½ years.

To all whom it may concern:

Be it known that I, FREDERICK L. STEEG, a citizen of the United States, residing at Chicago, in the county of Cook and State of Illinois, have invented a new, original, and ornamental Design for an Advertising Device, of which the following is a specification, reference being had to the accompanying drawing, forming a part thereof.

The figure is a front elevation of an advertising device, showing my new design.

I claim:

The ornamental design for an advertising device, as shown.

In testimony whereof, I have hereunto signed my name in the presence of two subscribing witnesses:

FREDERICK L. STEEG.

Witnesses:

JOHN W. HILL,
BERTHA HARTMANN.
